A. E. CARLSON

ELECTRIC GAS LIGHTER

Filed Aug. 7, 1922

Inventor:
A. E. Carlson
By: Wm. O. Baltz, Atty.

UNITED STATES PATENT OFFICE.

AXEL E. CARLSON, OF MOLINE, ILLINOIS.

ELECTRIC GAS LIGHTER.

Application filed August 7, 1922. Serial No. 580,100.

This invention relates to gas lighters and has for its principal object to make it possible to safely and conveniently use the alternating current of the ordinary lighting circuit to produce sparks at a burner sufficient to light gas escaping therefrom.

Further objects of the invention are to provide a gas lighter that is free from switches and similar troublesome elements, 10 that has a sparking point so located that it can be easily applied to the burner and without cramping or twisting the arm, and that can be conveniently hung near a stove or the like in a position easily accessible to 15 an adult, but out of the reach of children.

Further objects of the invention will become apparent as the description is read in connection with the accompanying drawing illustrating selected embodiments of the 20 invention, and in which

Fig. 1 is a longitudinal sectional view of one form of the invention hanging from a suitable bracket; and

Fig. 2 is a similar view of a modified form 25 of the invention.

Referring to Fig. 1 and the reference numerals thereon, 10 indicates a handle of wood, hard rubber or other suitable insulating material, which has a longitudinal bore 30 11 for the reception of a sparking rod 12 of any suitable metal. The sparking rod preferably projects from the front end of the handle a suitable distance and is then bent as indicated at 13 to form an arm 14 35 extending at an angle to the main body of the rod and terminating in a suitable point 15. The front end of the handle is counter-bored at 16 to receive a tube 17 of brass or other suitable material which encloses the 40 sparking rod up to the bend 13. This tube is preferably of larger interior diameter than the rod and asbestos or the like is packed in between the tube and the rod to a point adjacent to the end of the tube. A 45 nipple 19 of fibre or the like fits in the end of the tube and has a flange 20 extending across the end face of the tube and lying flush with its outer surface.

The rear end of the handle is counter-bored at 21 to receive a plug 22 of any suitable material such as fibre, bakelite, hard rubber and the like, which is equipped with a nut 23 adapted to screw on to the threaded end 24 of the sparking rod. As shown the 50 nut is provided with a tubular flange 25

which is threaded into the plug 22. A wire or cable 26 extends through a passage 27 in the plug and is soldered to the nut 23 at 28. This wire or cable may be of any suitable length which will depend upon the particular circumstances surrounding each use. The purpose of this wire is to connect the sparking rod with one side of the electric lighting circuit. It is understood that the other side is grounded, as is customary in 60 alternating circuits. The most convenient way of making this connection is to equip the wire with a plug adapted to enter the ordinary Edison socket, but of course it can also be electrically connected with the lighting circuit in other ways if desired.

A sufficient resistance should be interposed between the lighting circuit and the sparking rod to prevent blowing a fuse or otherwise injuring the wiring because of the low 70 resistance of the sparking rod.

In ordinary practice the sparking rod will be maintained in electrical connection with the lighting surface and therefore it is desirable to provide a hanger for the device 80 that will prevent it from accidentally coming in contact with any conductor or with any part of the body of the user. A convenient support is shown in section in Fig. 1 where 44 is a bracket of porcelain or like 85 material having a slot 45 in its front end communicating with a groove 46 which leads to a passage 47 in the base flange 48 by which the bracket is secured to the wall or other suitable support 49 by means of 90 screws 50. The arm 14 of the sparking rod is bent to form a bow 51 which receives a suitable rib 52 extending across the groove 46 and in conjunction with the passage 47 serves to hold the lighter securely in place. 95

By swinging the lighter to the position shown in dotted lines in Fig. 1, it can be easily withdrawn from the bracket and by reverse movement it is easily replaced with the arm 14 in the bracket and the weight of 100 the handle and other parts will serve to hold it secure in the position shown in Fig. 1 until it is desired for use when a slight swing outwardly to the dotted line position will permit it to be easily detached.

It is particularly important to have the arm 14 extending at an angle to the main body to the sparking rod for that permits the handle to be grasped in a convenient and easy manner and the point 15 to be ap- 116

plied to the burner or other place where the sparks are desired without any twisting of the wrist or raising or turning the arm. The particular angle shown is probably the most 5 convenient, but of course it can be varied to suit particular uses.

By eliminating switches and the like and connecting the sparking rod directly and continuously with the lighting circuit, I 10 eliminate a source of annoyance and trouble as well as an expensive element, and at the same time I have provided a construction in which the sparking rod is covered except at the arm 14 which when not in use lies within 15 in a bracket 44 and is therefore not exposed for contact with any conductor or with the person of the user. When the handle is grasped and the arm 14 freed from the bracket, the exposed part of the sparking 20 rod is away from the user and the point is very conveniently arranged for contact with the burner to be lighted.

In Fig. 2 I have shown a modified form in which the resistance is located within the 25 handle of the lamp lighter. In this case the handle 55 is counterbored from the rear to a shoulder 56 which receives the flange 57 of a nut 58 threaded on the end of a sparking rod 59. A resistance unit including the base 30 of insulating material 61, the coil 62, and the caps 63 and 64 is received in this counterbore. The coil 62 preferably lies in the helical groove of the base 61 and has its ends soldered or otherwise connected to the 35 contact caps 63 and 64. The rear end of the counterbore is threaded at 65 to receive a plug 66 which has a contact piece 67 that presses a spring 68 against the cap 64 and thereby forces the cap 63 into proper contact with the nut 58. The contact piece 67 is connected with a cable 69 leading to a suitable plug or other device for electrical connection with the lighting circuit. The handle 55 is provided with suitable 40 ventilating openings 70 leading into the counterbore and adjacent to the coil 62 of the resistance unit. The operation of this form is substantially the same as that in Fig. 1 and it permits the resistance unit to be 45 housed within the handle of the lamp lighter and enables the wire 69 to be connected directly to the lighting circuit, or to any suitable plug of conventional form.

I am aware that changes may be made in 50 the form, construction and arrangement of the invention, as set forth in the selected embodiment herein, without departing from the scope or sacrificing any of its material advantages, and I therefore reserve the right 55 to make all such changes as fairly fall within the scope of the following claims:

I claim:

1. The combination of a gas lighter including a sparking rod having an arm extending laterally therefrom, a bracket of

insulating material adapted to receive said arm, and means for interlocking said arm with said bracket.

2. The combination of a gas lighter including an insulating handle, a sparking rod mounted in said handle and having an arm extending laterally therefrom and bent to form a loop, and a bracket of insulating material adapted to receive said arm and having means to co-act with said loop. 70

3. The combination of a gas lighter including a sparking rod having an arm extending laterally therefrom, an insulating support having a groove open at the top to receive said arm, and means for holding the arm in said groove. 75

4. The combination of a gas lighter including a sparking rod having an arm extending laterally therefrom, an insulating support having a groove open at the top to receive said arm, a passage to receive the point on the arm, and means for holding the arm in said groove. 80

5. The combination of a gas lighter including a sparking rod having an arm extending laterally therefrom, an insulating support having a slot at one end to receive said arm, and means for holding the arm in said slot. 85

6. The combination of a gas lighter including a sparking rod having an arm extending laterally therefrom, an insulating support having a slot at one end to receive said rod, a groove extending from said slot to receive said arm, and a passage at one end of said groove to receive the point of said arm. 90

7. The combination of a gas lighter including a sparking rod, an arm extending laterally therefrom, an insulating support having a slot at one end to receive said rod, a groove extending from said slot to receive said arm, a passage extending from said groove to receive the point of the arm, and means in the groove for interlocking with the arm. 100

8. The combination of a gas lighter including a sparking rod having an arm extending laterally therefrom, and an insulating support for the lighter having means to engage the arm and the point of the arm and that part of the rod which connects with the arm to support the lighter and prevent it from swinging laterally or inwardly. 115

9. The combination of a gas lighter including a sparking rod having an arm extending laterally therefrom, an insulating support for the lighter, and means on said support for holding the lighter in engagement therewith and for restricting the swinging movement of the lighter on the support to a limited outward movement for disengagement of the lighter from the support. 120

10. In an electric gas lighter, the combination of a handle having a bore extending 125

therethrough and a counterbore at each end thereof communicating with said bore, a sparking rod extending through said bore and terminating in a laterally directed arm,
5 a plug seated in the counterbore at the rear end of said handle and connecting with said sparking rod, a tube seated in the counterbore at the front end of said handle, and surrounding said sparking rod, and insu-
10 lating material between said tube and said sparking rod.

11. In an electric gas lighter, the combination of a handle having a bore therein and a counterbore at its front end communicating with said bore, a sparking rod seated in said bore and projecting forwardly from said handle, a projecting sleeve seated in said counterbore and encircling the projecting portion of said sparking rod, and a laterally directed arm carried by said sparking rod 15 having a sparking point at the end thereof. 20

AXEL E. CARLSON.
